CLAIM

We claim the ornamental design for a mini merchandise case, as shown and described.

DESCRIPTION

This application is related to U.S. Design application Ser. No. 29/597,039, filed Mar. 14, 2017, and titled Large Merchandise Case.

FIG. 1 is a top, front, and right side perspective view of a mini merchandise case showing my new design;

FIG. 2 is a top, back, and left side perspective view thereof;

FIG. 3 is a bottom, back, and right side perspective view thereof;

FIG. 4 is a top view thereof;

FIG. 5 is a bottom view thereof;

FIG. 6 is a right side view thereof;

FIG. 7 is a left side view thereof;

FIG. 8 is a front side view thereof;

FIG. 9 is a back side view thereof; and,

FIG. 10 is a front view of the open case, exposing top inner inserts thereof.

The broken lines around the exterior and interior perimeter of a mini merchandise case's body illustrate surface ornamentation. The remaining broken line hinges, latch, and interior compartments illustrate portions of the mini merchandise case. None of the broken lines illustrated in the figures form part of the claimed design.
